UNITED STATES PATENT OFFICE.

JACOB DIEHL, OF ASHLAND, WISCONSIN, ASSIGNOR OF ONE-HALF TO WILLIAM L. BEAN, OF VIRGINIA, MINNESOTA.

BURNER.

Application filed May 22, 1922. Serial No. 562,696.

To all whom it may concern:

Be it known that I, JACOB DIEHL, a citizen of the United States, residing at Ashland, in the county of Ashland and State of Wisconsin, have invented a new and useful Burner, of which the following is a specification.

This invention relates to fuel burners, and more particularly to a burner especially designed for burning crude oil.

The primary object of the invention is to provide a burner of this character wherein the heat from the burning oil will be utilized for vaporizing the incoming oil to facilitate the operation of the burner.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a side elevational view of a burner constructed in accordance with the present invention.

Figure 2 is a longitudinal sectional view through the burner.

Figure 3 is a bottom plan view of the burner.

Figure 4 is a top plan view.

Figure 5 is a plan view of one of the burners proper.

Figure 6 is an end elevational view of the burner.

Referring to the drawings in detail, the reference character 5 designates the base of the burner, which is rectangular in formation, and provided with downwardly extending flanges 6, formed along the longitudinal edges thereof.

Formed in the base 5 at points adjacent to the ends thereof are circular openings provided with inwardly extending flanges 7 cooperating with the flanges 8 formed on the burners proper for supporting the burners in proper relation with respect to the base.

Each of these burner elements is formed

with a groove or pocket indicated at 9, there being formed a central opening 10 in the respective burners through which the liquid fuel passes to the combustion chamber to be hereinafter more fully described. A central opening indicated at 11 is formed in the base and receives the downwardly extended portion 12 of the upper portion of the burner for directing air to the burner chambers 13, which are disposed directly over the burners proper, and are indicated generally by the reference character 14.

The upper portion 22 of the burner is divided by the wall 15 forming lateral passageways for the air passing through the burner, dampers 17 being mounted in the passageway for controlling the volume of air passing to the burner chambers. Openings 18 are formed in the upper portion of the burner, which openings communicate with the central openings 10 of the burners proper through the angularly disposed openings 19.

As shown, the upper portion of the burner is disposed in spaced relation with the lower portion thereof to provide spaces 20 to permit the flame to pass outwardly under the upper portion. Lugs 21 are provided on the upper portion and contact with the lower portion for supporting the upper portion in such spaced relation.

It is to be understood, that the burner as herein described and shown, is of the down-draft type, the air entering the burner through the lateral passageways, where the same circulates through the burner proper.

It might be further stated that the burner is especially designed for use in range fireboxes, wherein the range may be converted from a coal burning structure to a structure wherein liquid fuel may be employed.

In the use of the burner, the upper portion thereof is removed, and a quantity of fuel is placed in the pocket 9 and lighted to heat the burner proper. When the burner has become sufficiently heated, liquid fuel is supplied through the openings 10, the openings 10 being in communication with a suitable source of liquid supply not shown.

It is obvious that as the liquid fuel contacts with the heated burner the same becomes readily vaporized and easily ignited.

The damper 17 may now be operated to regulate the quantity of air entering the burner chambers.

Having thus described the invention, 5 what is claimed as new is:—

In a fuel burner, a base having a central opening and having lateral openings, flanges formed on the walls of the lateral openings, burners formed with grooves and having 10 flanges adapted to rest on the flanges of the walls of the lateral openings to support the burners, each of said burners including an upwardly extended central portion having obliquely disposed openings, an upper portion, 15 a wall in the upper portion for divid-

ing the upper portion into lateral passageways, said upper portion having openings disposed above the obliquely disposed openings to permit air to pass through the upper section and contact with the burners, and 20 means for controlling the passage of air through the upper section.

In testimony that I claim the foregoing as my own, I have hereto affixed my signature in the presence of two witnesses.

JACOB DIEHL.

Witnesses:

G. G. MACDONALD,
J. B. MATHEWS.
